BRICK CARRIER.

Application filed February 13, 1925. Serial No. 8,926.

This invention relates to improvements in brick carriers.

The primary object of the invention is to provide a brick carrier that may be manipulated easily with one hand for causing the same to grip and release a series of bricks.

A further object of the invention is to provide a carrier for holding the brick gripping members in a proper relation in respect to each other so that the carrier may be placed in a position for taking hold of a predetermined number of bricks, whereupon the said members become inoperative and the bricks may be gripped, the said members again automatically becoming operative when the bricks are released from the carrier so that a new load of bricks may be handled.

Other objects and advantages of the invention will be apparent during the course of the following description.

In the accompanying drawings forming a part of this specification and in which like numerals are employed to designate like parts throughout the same,

Figure 1 is a side elevational view of the brick carrier embodying this invention,

Figure 2 is a longitudinal sectional view taken upon lines II—II of Fig. 1,

Figure 3 is a transverse sectional view taken upon line III—III of Fig. 1, and

Figure 4 is a transverse sectional view taken upon line IV—IV of Fig. 1.

In the drawing, wherein for the purpose of illustration is shown a preferred embodiment of this invention, the numeral 5 designates in its entirely the body portion of the carrier which consists of the telescopically arranged tubular members 6 and 7 which are of square formation in cross-section with the member 7 being received within the member 6. For the purpose of maintaining these members 6 and 7 in their proper adjusted position, the member 7 has a series of apertures 8 formed in one side wall thereof which are adapted to be selectively arranged in alignment with an aperture 9 formed in the adjacent wall of the member 6. Suitably secured to the outer face of this wall of the member 6 is a latch plate 10 having a stud 11 which enters the registering openings 8 and 9. This latch plate 10 is provided with a grip member 12 by means of which the stud 11

may be operated. To maintain this latch plate with its stud in operative positions in respect to the telescopic members 6 and 7, a spring plate 13 is secured to the side wall of the member 6 by the screws 14 and 15. The free end of the plate 13 has its free end overlying the latch plate 10.

Removably fastened to the free end of the frame member 7 is an inverted L-shaped brick gripping member 15 which is maintained in place by the bolt 16. The free end of this gripping member 15 is bifurcated, as at 17, for providing an increased gripping surface.

Pivotedly connected to the free end of the frame member 6, as by the bolt 18, is a second brick gripping member 19 having the bifurcated free end 20 and the inwardly curved upper end 21 having the apertured ear 22 formed on its end. The aperture in this ear 22 is intended for receiving the bolt 23 which secures the hand grip 24 to the member 19. For the purpose of maintaining this gripping member 19 in a position to permit the carrier to be arranged in respect to a series of bricks so that the latter may be grasped, a spring member 25 is secured by the screws 26 to the under face of the frame member 6 and has adjustably secured to its free end the yoke member 27, as by the slot 28 and screws 29. This yoke member 27 has the bifurcated end 27^a formed with its furcations bent to define hook portions 30 which releasably engage the transversely extending stud 31 carried by the brick gripping member 19.

The operation of this brick carrier may be described as follows:

It is to be understood that the pivotal brick gripping member 19 is retained in the position shown in Figs. 1 and 2 by the yoke 27 carried by the spring member 25. With the brick gripping members 15 and 19 in the relative positions illustrated, the carrier is adapted to be positioned in operative relation with a predetermined series or number of bricks arranged in a pile. The operator of the carrier merely grasps the handle 24 with one hand and inserts the brick gripping members 15 and 19 between the adjacent faces of the bricks. By forcing downwardly upon the carrier, by means of the handle 24, the bricks to be moved will be forced in engagement with the brick grip holding yoke 27 for moving the same

toward the frame member 6 to release the hooked ends 30 from the transversely extending stud 31. After the brick gripping member 19 is released, an upward lifting force applied to the handle 24 will cause the member 19 to pivot upon the pin 18 for gripping or binding the bricks to be handled between the member 19 and 15. This series of bricks may then be carried 10 to the place desired and by placing the said bricks upon a support, the handle 24 may be moved downwardly in respect to the frame 5. This downward movement will increase the distance between the members 15 and 19 and the bricks will be released. This pivotal movement of the brick gripping member 19 will cause the stud 31 to be again moved into engagement with the hooks 30 and the member 19 will be retained 20 in the position illustrated in Figs. 1 and 2.

It is to be understood that the form of this invention herewith shown and described is to be taken as a preferred example of the same, and that various changes in the 25 shape, size, and arrangement of parts may be resorted to without departing from the spirit of the invention or the scope of the subjoined claims.

Having thus described the invention, I 30 claim:—

1. In a device of the type described, a frame comprising a pair of telescopically arranged tubular members, means for maintaining said members in adjusted relation

in respect to each other, a gripping member 35 rigidly carried by one of the frame members, a second gripping member pivotally carried by the remaining frame member, a handle carried by the pivoted gripping member, means for releasably holding the 40 pivoted gripping member immovable in respect to the rigid gripping member and length adjusting means for said holding means whereby the same is adapted to correspond for operative positioning at different adjustments of the tubular members. 45

2. In a device of the type described, a frame comprising a pair of telescopically arranged tubular members, rectangular in cross-section, means for maintaining said 50 members in adjusted relation in respect to each other, a gripping member rigidly carried by one of the frame members at the free end thereof, a second gripping member pivotally carried by the opposite end of 55 the remaining frame member, a handle carried by the pivoted gripping member, and means for releasably holding the pivoted gripping member immovable in respect to the rigid gripping member, said means being released by the objects to be handled when the device is properly arranged in respect thereto.

In testimony whereof we affix our signatures.

HARVEY K. SCHONDELMAYER.
SAMUEL C. FULKERSON.
